SCREENING DEVICE

Seth J. Gilson, Mercer, Pa., assignor to Heath
Smith, Mercer, Pa.

Application October 14, 1940, Serial No. 361,150

10 Claims. (Cl. 209—319)

My invention relates to a screening device for crushed stone, gravel, slag, sand and similar materials. It is particularly useful for testing samples of such materials, which it accomplishes in a highly efficient manner, the tests being speedy and extremely accurate as to the sizes and proportions of the constituent parts of the material tested, while the operations necessary to the tests are simple and easy to perform, and many operations heretofore necessary in prior testing devices are eliminated.

In its more specific aspect my invention contemplates the use of screening instrumentalities comprising a series of screen trays tightly bound together for operation as a single rigid unit, which unit, preferably, is freely suspended vertically from the main stationary supporting frame, the suspension being preferably cushioned by supporting springs between the main frame and the unit whereby vibration of the fixed or supporting frame is minimized and substantially eliminated, the spring connections serving as shock absorbers. The unit is preferably centered top and bottom, conveniently by rods attached thereto, which also may constitute the means for binding its parts together, said rods advantageously extending through bushings in the top and bottom of the fixed frame to insure vertical reciprocation of the unit. In order to maintain the suspension characteristic of the unit, the driving mechanism for reciprocating it is preferably mounted on top of the fixed frame and connected to the unit by vertically suspended links, which are reciprocated by cams operated by said driving mechanism. This location of the drive mechanism further permits the trays to occupy a lower position where they are more accessible to the operator. When the fixed frame is properly leveled, vertical operation is assured. By reason of the compactness and freedom from external vibration of my structure, it is possible to operate the screens at a much higher speed than similar devices of the prior art, and this higher speed enables me to employ a shorter amplitude of vibration of the unit.

A most important aspect of my invention is the construction of the oscillating unit whereby the screen trays therein may be tightly bound together for the screening operation, yet by simple loosening of the binding mechanism any single tray may be independently removed and also anyone or more of the plurality of trays may be left out if the character of the tests being made do not require their use. These operations may be simply accomplished by a system of spacers

and accessory parts devised by me. Each tray compartment in the unit is preferably tightly sealed on two sides and the rear against escape of any material therefrom, while at the front an open space is provided for inspection of the operation as it proceeds. Each tray, when empty, is balanced to weigh the same as each other tray, balancing weights being applied, as necessary, to the individual trays to effect this result. This permits a single reading of the scale to determine the weight of the contents of any given tray.

A further important feature of my invention is the location of the dust pan in a fixed position below the reciprocating frame whereby it remains stationary, whereas in prior constructions it was mounted as part of the movable tray unit.

All of the moving parts are contained within the outer or main frame, which is so constructed as to avoid contact by the operator with moving parts and thereby the highest degree of safety to the operator is insured.

Further features and advantages of my invention will hereinafter appear.

The accompanying drawings show for purpose of exemplification, but without limiting my invention or claims thereto, preferred embodiments of my invention.

In said drawings:

Fig. 1 is a perspective view of my complete screening device in which the larger trays are employed in the oscillating unit; Fig. 2 is a perspective view of a spacer member employed in said unit; Fig. 3 is a front elevation partly in section showing features of my driving mechanism for oscillating said unit; Fig. 4 is a transverse vertical section on the line 4—4 in Fig. 1; and Fig. 5 is a transverse vertical section of one of the trays.

Referring to the drawings, there is shown (Figs. 1 and 4) a stationary frame 1 having suspended for vertical reciprocation therein a rigid tray unit 2 and driving mechanism 3 for said unit.

The stationary frame 1 is preferably closed on its two sides and rear, while open at the front to permit access to the interior of the casing and inspection of the trays.

The reciprocating tray unit 2 comprises an upper rectangular frame member 5 preferably made of angle iron and a similar lower frame member 6, the latter being open at its front end, its free front ends being tied together by an inverted U-shaped tie member 7; located between the upper and lower frame members 5 and 6 are a series of U-shaped spacers 8 outwardly flanged at their upper and lower ends. Said upper and

lower frame members and spacers are bound together to form the reciprocating unit by tightening rods 9 passing freely through openings 11 in the internal flanges 10 at the top of the main casing and preferably through recesses or openings 12 midway the side flanges of the spacers 8, said rods being provided with screw threads at their lower ends on which are mounted nuts 13 rigidly attached as by welding to the underside of the lower frame member 6, said rods being provided at their upper ends with stop collars 14 rigidly attached thereto as by welding, which are of a size sufficiently small to permit their being introduced with the rods through the opening 11 in the flange 10, but sufficiently large to prevent them passing through the opening in the upper frame member 5 through which the rods pass. In order to insure true vertical reciprocation of the reciprocating unit, a bearing member 15 (placed on said rods above the collars 14 before the latter are welded to the rods) are secured to the tops of the internal flanges 10, over the openings 11, and a similar bearing 16 is secured to the underside of the U-shaped lower frame member 17 made of angle iron, which reinforces the bottom of the main stationary frame 1. The bearing member 16 is of a size to fit the lower reduced ends 18 of said rods. Said rods are provided at their top ends with means for turning the same in the bearings, such means being herein shown as crank extensions 19 formed on the upper ends of the rods. The reciprocating unit 2 is designed to carry a plurality of screen trays 20, each provided with appropriate screen mesh bottom 21. These trays are provided at their upper ends with outwardly extending flanges 22, said trays being of less depth than said spacers 8, and each tray being adapted to be slid into the reciprocating unit 2, its flange 22 passing between the upper flange on a spacer and the lower flange of the spacer immediately above said first mentioned spacer. The flanges of the top tray are similarly adapted to lie between the horizontal flange of the upper frame member 5 and the upper flanges of the uppermost spacer member 8. A stationary dust pan 20a is supported by the lower frame member 17 below the reciprocating tray unit 2.

In order to preserve a sufficient space between the respective spacers 8 and between the upper spacer and the upper frame member 5 to permit these trays to be freely introduced, I provide spacer rods 23 having at their top heads 24 to engage the frame member 5, or welded thereto, said rods extending downwardly freely through openings 25 in the flanges of the spacer members and frame member 6, their lower ends being provided with enlarged heads 26 rigidly fixed thereon as by welding and incapable of passing through said openings. These heads serve to limit the distance of the lower frame member 6 from the upper frame member 5. Also, permanently attached to the spacer rods 23 are stop members 27, each located a sufficient distance below the corresponding upper flange of a spacer member 8 to prevent its spacer member dropping below it, said stops being larger than the corresponding openings in the flange of the spacer members. These stops are so located that each spacer member will be retained in position sufficiently below the spacer member above it to permit the flanges 22 of the trays to freely slide between them. As shown in the drawings, three such spacer rods are provided, one in the center of the rear of

the unit, and one on each side near the front, their positions being more clearly indicated by the positions of the corresponding flange openings 25 in the spacer flanges in Fig. 2. Any variation in the number or location of these spacer rods, which will insure adequate support for the spacers, may, of course, be employed.

When the trays have been slid into their respective positions, with their flanges between the flanges of the spacers and top frame member, the crank members 19 are turned to raise the bottom frame member 6 upwardly and bind the flanges of the trays, spacers and upper frame member tightly together into a rigid unit. When it is desired to release the trays, the crank members 19 are operated to lower the frame member 6, thereby relaxing the clamping action on each tray flange and permitting any individual tray to be removed independently of any other tray.

The reciprocating unit 2 as a whole is resiliently mounted as a suspension member in the main frame by means of suspension rods 28, preferably located at each corner of the stationary frame and attached thereto at their upper ends by heads 29, said rods passing through openings in the horizontal flanges of the upper frame member 5 and carrying two springs 30 and 31, one located above said horizontal flanges and the other below them, the lower end of the lower spring resting upon a stop member 32 fastened to the bottom of said rods. The vertical flanges of the upper frame member 5 lie within the down-turned flange 33 of the stationary outer casing in order to protect the operator from the moving parts. Access to the rear suspension rod assemblies is effected through appropriate openings in the rear side of the main casing.

The main frame is provided on its top with the top member 35, to which is attached an angular member 36, which supports the drive casing 37 attached therethrough through appropriate fasteners 38. As more clearly shown in Fig. 3, the drive member comprises a driven shaft 39 suitably journaled in the drive casing as shown, said shaft being provided at its opposite ends with eccentric or cam portions 40 on which are journaled link members 41, having bearings 42 at their lower ends adapted to have seated therein the rod 43, which passes through openings in U-shaped ears 44, one leg of each ear being secured as by welding to the upper frame member 5 of the vibrating unit 2. In assembling, the drive mechanism may readily be connected to the tray unit 2 by inserting a pin or the like in the openings 45 in the main casing opposite the end of the rod 43, then driving said rod endwise in the direction of the far side until the link 41 can drop to its vertical position with its lower bearing in line with the end of said rod, then performing the same operation at the other side to permit lowering of the link 41 on that side, and finally centering said rod 43 by means of said pin until complete connections are effected between said link and said rod.

The edges of the screen member 21 of the tray 20 are preferably provided with a sheet metal binding with its outer edges turned in the form of a hook 46, as clearly shown in Fig. 5. Plate members 47 secured to the sides and ends of the tray by bolts 48 and provided on their lower edges with hook members 49, to engage the hook members 46 on the screen provide a convenient means of tensioning the screen, when needed, thus preventing sags and distortions of the screen members. The trays are balanced so

that each will be of the same weight and this is conveniently effected by use of shims 50 of selected weight located under the nuts 51 on said bolts.

In the operation of the device, the crank members 19 are operated to rotate the rods 9 in the nuts 13 fixed to the lower frame 6 until the spacers 8 drop on their respective stops 27, leaving spaces between adjacent spacers and the top member 5 to permit insertion of the trays 20, their flanges sliding over the top flanges of the spacers into the positions shown in Fig. 1. Thereupon, the rods 9 are turned by the crank members 19 in the opposite direction to lift the lower member 6 until all of the spacer members and trays are rigidly locked together. Material having been fed into the top of the machine, the driving mechanism is then set in operation, which operation may be observed through the open front of the main casing. When the screening operation has reached the desired point, the driving mechanism is stopped and the trays are released in the manner above indicated. Since all of the trays are now freed from the clamping action of the spacers, any single tray may be individually removed independently of any other tray, and also the vibrating unit may be operated with as many trays as may be desired. The springs 30 and 31 cushion the vibration and the bearings 13 and 15 at the top and bottom of the main casing maintain the rods 9 in vertical position, thus insuring a balanced system, a minimum of vibration being imparted to the outer frame.

While I have specifically described certain preferred forms of my invention, it is obvious that it is capable of embodiment in various forms and modifications, and many features of my invention may be used without the conjoint use of other features, as conditions may indicate to be desirable.

I claim:

1. A screening device comprising a main stationary frame, a screen unit suspended from the top of said main frame for vertical reciprocatory movement, means located at the top of said main frame for vertically reciprocating said unit, said unit comprising upper and lower frame members, screen trays and tray spacer members alternately therebetween, and means for moving said upper and lower members toward each other to clamp said trays and tray spacer members between them to form a rigid unit, or away from each other to release said trays and spacers from said clamping engagement to permit removal of one or more of said trays, said means for moving said upper and lower frames toward and away from each other having vertical reciprocatory engagement with said stationary frame to compel vertical reciprocation of said unit.

2. A screening device comprising a main frame portion, a screen unit mounted for vertical reciprocatory movement in said main portion, said unit comprising upper and lower frame members, screen trays and tray spacer members, each provided with flanges, between said upper and lower frame members, the flanges on said trays lying between adjacent flanges of said spacer members, a binding rod passing through said upper and lower frame members and provided above said upper frame member with a fixed stop preventing upward movement thereon of said upper frame member, and provided in the region of said lower frame member with screw threads carrying a stop nut in engagement with

the bottom side of said lower frame, said rod being rotatable in opposite directions to cause said nut to bind together or loosen, respectively, the members of said unit, the ends of said rod projecting through bearings at the upper and lower ends of said main frame to permit the unit to reciprocate in vertical direction, only.

3. A screening device comprising a main frame portion, a screen unit mounted for vertical reciprocatory movement in said main portion, said unit comprising upper and lower frame members, screen trays and tray spacer members, each provided with flanges, between said upper and lower frame members, the flanges on said trays lying between adjacent flanges of said spacer members, and a binding rod passing through said upper and lower frame members and provided above said upper frame member with a fixed stop preventing upward movement thereon of said upper frame member, and provided in the region of said lower frame member with screw threads carrying a stop nut in engagement with the bottom side of said lower frame, said rod being rotatable in opposite directions to cause said nut to bind together or loosen, respectively, the members of said unit.

4. A screening device comprising a screen unit comprising upper and lower frame members, screen trays and tray spacer members, each provided with flanges, between said upper and lower frame members, the flanges on said trays lying between adjacent flanges of said spacer members, and rods attached at one end to said upper frame member and passing freely through openings in the flanges of said spacers and said lower frame member, said rods being provided with adjustable means engaging said lower frame member, which in one position binds said trays and spacers together and in another position releases said binding effect to permit individual removal of said trays and fixed stops on said rods, each located sufficiently below the flange of its corresponding spacer when the trays or spacers are bound together to hold the same sufficiently far from its adjacent spacer when said spacers are released to permit the tray whose flange lies therebetween to be readily slid out of the unit.

5. A screening device comprising a screen unit having upper and lower frame members, alternate screen trays and tray spacer members between said frame members, and means for binding said parts rigidly together or for releasing them, rods attached at one end to said upper frame member, and stops fixed at points on said rods to hold said spacer members sufficiently apart when released to permit withdrawal of any individual tray or trays.

6. A screening device comprising a screen unit having alternate screen trays and tray spacer members, means operable to bind said members together as a rigid unit, or to release them, and means to hold said spacer members sufficiently apart when released to permit withdrawal of any individual tray or trays.

7. A screening device comprising a screen unit having alternate screen trays and tray spacers, said spacers being substantially U-shaped in horizontal cross-section and provided with flanges at their top and bottom edges, said trays being provided with flanges at their top edges, normally adapted to lie between flanges of adjacent spacers, and means for clamping said trays and spacers together whereby a dust proof seal is provided between said unit and the exterior thereof on two sides and the rear.

8. A screening device comprising a screen unit having alternate screen trays and tray spacers, said spacers being substantially U-shaped in horizontal cross-section, and means for clamping said trays and spacers together whereby a dust proof seal is provided between said unit and the exterior thereof on two sides, and the rear.

9. A screening device comprising a screen unit having alternate screen trays and tray spacers of greater vertical height than said trays, said spacers being substantially U-shaped in horizontal cross-section and provided with flanges at their top and bottom edges, said trays being provided with flanges at their top edges, normally adapted to lie between flanges of adjacent spacers, and means for clamping said trays and spacers together whereby a dust proof seal is provided between said unit and the exterior thereof on two sides and the rear, and inspection openings are provided over the tops of said trays, at 20 the front.

10. A screening device comprising a main frame portion, a screen unit mounted for vertical reciprocatory movement in said main portion, said unit comprising upper and lower frame members, screen trays and tray spacer members, each provided with flanges, between said upper

and lower frame members, the flanges on said trays lying between adjacent flanges of said spacer members, a binding rod passing through said upper and lower frame members and provided above said upper frame member with a fixed stop preventing upward movement thereon of said upper frame member, and provided in the region of said lower frame member with screw threads carrying a stop nut in engagement with the bottom side of said lower frame, said rod being rotatable in opposite directions to cause said nut to bind together or loosen, respectively, the members of said unit, the ends of said rod projecting through bearings at the upper and lower ends of said main frame to permit the unit to reciprocate in vertical direction, only and other rods attached at one end to said upper frame member and passing freely through openings in the flanges of said spacers and said lower frame member and fixed stops on said last mentioned rods, each located sufficiently below the flange of its corresponding spacer to hold the same sufficiently far from its adjacent spacer to permit the tray whose flange lies therebetween to be readily slid out of the unit.

SETH J. GILSON.
